Primary Examiner — Zenia Bennett*(74) Attorney, Agent, or Firm* — QuickPatents, Inc.; Kevin Prince(57) **CLAIM**

I claim the ornamental design for an attachable braid, as shown and described.

DESCRIPTION

FIG. 1 is a perspective view of an attachable braid, showing my new design in an in-use configuration;

FIG. 2 is a front elevational view thereof, illustrated in a flat configuration;

FIG. 3 is a rear elevational view of FIG. 2;

FIG. 4 is a right-side elevational view of FIG. 2;

FIG. 5 is a left-side elevational view of FIG. 2;

FIG. 6 is a top plan view of FIG. 2; and,

FIG. 7 is a bottom plan view of FIG. 2.

The broken lines showing a motorcycle helmet in FIG. 1 depict environmental matter and form no part of the claimed design.
